UNITED STATES PATENT OFFICE.

PAUL GROSS, OF DUSSELDORF, GERMANY, ASSIGNOR TO GENERAL DENTAL COMPANY
GEBRÜDER FUNKE, OF DUSSELDORF, GERMANY.

MANDREL FOR DENTAL DISKS.

1,071,228.

Specification of Letters Patent. Patented Aug. 26, 1913.

Application filed February 4, 1913. Serial No. 746,119.

To all whom it may concern:

Be it known that I, PAUL GROSS, a subject of the German Emperor, residing at Dusseldorf, Germany, have invented a new and useful Mandrel for Dental Disks, of which the following is a specification.

This invention relates to a mandrel for dentists' use, which is provided with novel and efficient means for fitting a grinding, 10 polishing or similar disk to the mandrel head.

In the accompanying drawing: Figure 1 is a side view partly in section of a mandrel embodying my invention; Fig. 2 a similar view with the plug and grinding disk removed; Fig. 3 an end view of the mandrel; Fig. 4 a section on line $y-z$; Fig. 1, and Fig. 5 a side view of the plug.

The stock 4 of the mandrel A is provided 20 at one end with a head 1, a tapering section 2, back of the head, and a bead 3 back of the tapering section. Head 1 and tapering section 2 are slotted diametrically as at 5 to subdivide the same into a pair of opposed spring jaws, the slit 5 opening into a transverse bore 7. The two inner faces of the spring jaws are grooved as at 8 and into these grooves opens a second transverse bore 9 arranged at right angles to bore 7. Tapering section 2 is encompassed by a slidable ferrule 6, by means of which the jaws may be contracted, the movement of said ferrule being checked by bead 3.

Head 1 is provided with teeth 10 adapted 35 to pierce the grinding, polishing or other disk 11, which is to be fitted to the tool head. These teeth are adapted to enter the grooved base 15 of a plug 13 which is adapted to engage the outer face of disk 11 and to be

removably secured to mandrel A. For this latter purpose, plug 13 is provided with a shank 12 which is adapted to be grasped by the spring jaws, the shank being provided with a bead or bulged section 14 which is adapted to engage grooves 8. The diameter 40 of this bead is a little larger than that of the channel formed between grooves 8, so that on sliding the stem 12 inward in the axial direction of the tool shank, the bead 14 will force the spring jaws apart, until it 45 becomes seated within bore 9 whereupon the jaws will spring together and may be locked in their contracted position by ferrule 6. In this way, the dental disk 11 will become securely grasped between the plug and the 50 head of the mandrel.

I claim:

1. A mandrel for dental disks, comprising a headed stock which is split to form a pair of spring jaws, grooves extending along the 60 inner faces of said jaws and a transverse bore opening into the grooves combined with a plug having a stem, and a bead on said stem adapted to engage the grooves.

2. A mandrel for dental disks, comprising a stock having a head and a tapering section back of the head, said head and tapering section being split to form a pair of spring jaws, grooves extending along the inner faces of said jaws and a transverse bore opening 70 into the grooves, combined with a plug having a stem and a bead on said stem adapted to engage the grooves, and a ferrule 75 slidable on the split tapering-stock section.

PAUL GROSS.
